UNITED STATES PATENT OFFICE.

SAMUEL GREENBERG, OF SYRACUSE, NEW YORK.

PUSH BROOM.

Application filed January 5, 1925. Serial No. 594.

To all whom it may concern:

Be it known that I, SAMUEL GREENBERG, a citizen of the United States, residing at Syracuse, in the county of Onondaga and State of New York, have invented certain new and useful Improvements in Push Brooms, of which the following is a specification.

This invention relates to improvements in push brooms or brushes, designed for sweeping or cleaning streets, as well as the floors of factories, mills, and dwellings, and has for its object to provide a novel and simple cleaning device of the class, comprising an elongated body or back, from which depend the flexible twigs or branches of the common broom corn, by which the sweeping is effected. A further object is to provide a push broom, wherein a plurality of relatively small individual brush units are applied to the common back, the said units being arranged in rows or staggered, and adapted to be replaced when worn out, without disturbing the adjacent units. The said individual units are rigidly mounted upon wooden cores, which are inserted in aligning or staggered perforations formed in the back, to which they are made rigid. A further object is to provide a hood, which is arranged to enclose the back of the broom, to prevent spreading and straggling of the units, as well as to shield the back and the tops of the individual units from moisture and dirt. And a further object is to provide a relatively long handle for manually propelling the broom over floors, pavements, and other surfaces.

I attain these objects by the means set forth in the detailed description which follows, and as illustrated by the accompanying drawing, in which—

Figure 1 is a front side elevation of the complete push broom with the hood and handle attached. Fig. 2 is a top plan view of the same. Fig. 3 is the top plan view of the broom with the hood removed. Fig. 4 is a side elevation of the same, with portions broken away for showing the manner of attaching and securing the individual units which comprise the composite structure of the broom. Fig. 5 is an end elevation of the broom shown in Figs. 1 and 2. Fig. 6 is a side view of one of the individual units. Fig. 7 is a top end view of the same. Fig. 8 is a skeleton view of a broom comprising a single row of the individual units. And Fig.

9 is a vertical cross-section taken on line 9 of Fig. 8.

In the drawing, 2 represents the body or back of the push broom, which is preferably made of a single elongated piece of wood, the said body preferably being provided with a number of vertical perforations 2', which may be arranged in staggered rows, as shown in Fig. 3, or in a straight row, as shown in Figs. 8 and 9. The sweeping or cleaning element comprises a number of brush units 3 and 3', which are preferably made up by binding bristles preferably formed of the twiggled heads of broom corn about round wooden cores 3^a with wires 3^c. The mode of making these individual units may be the same as employed for making the common house brooms. The cores 3^a preferably extend a short distance above as well as below the top ends of the bristles, and their free ends are driven into the perforations 2' of the back, as shown in Figs. 3, 4, 5 and 9. The wires 3^c are usually held from uncoiling by means of nails 3^d. My push brooms are usually made up in several sizes: the larger size, as shown in Figs. 1 to 5 inclusive, being suitable for sweeping streets, and the floors of factories, warehouses, mills and the like. In these larger brooms, the individual units 3—3' are generally arranged in two or more rows, as best seen in Figs. 3 and 5. The individual units 3 are preferably elliptical in cross-section, and are arranged to present their broad faces to the work like ordinary brooms, as may be understood from Figs. 1, 3, 4, 5 and 7, and these larger brushes are preferably disposed in two rows in staggered relation, for preventing the sweepings from escaping between the units, as well as for reinforcing and bracing said units, as best seen in Fig. 3. This staggering of the individual units ordinarily leaves vacant spaces, as 4, at the opposite ends of the back 2, which are not large enough to accommodate the oval units. These vacant corners are usually filled in for completing and balancing the broom, by means of smaller round units as 3' (see Fig. 3). After the individual units 3—3' are applied to the back 2, by driving the cores 3^a tightly into the perforations 2', the several units are held from rotation and from accidental release from the body 2, by means of pins 105 or nails 5, which may be driven transversely through the body and the cores, as shown

110

- in Figs. 3, 4, 8 and 9. 6 represents an elongated sheet metal cap or hood, which is mounted upon the body 2 (see Figs. 1, 2 and 5), to which the hood may be secured 5 in any suitable manner, as by nails or screws 6'. The drooping flanges or balances of the hood preferably extend a considerable distance below the bottom plane of the body 2, and tend to hold the twigs or bristles of the units 3-3' from spreading, straggling or breaking during the sweeping or other handling of the broom. The hood 6 also tends to prevent moisture and dirt from reaching the head 2 and fouling, rotting or otherwise injuring the top ends of the units 3-3'.

In Figs. 8 and 9 I have shown a push broom of smaller size, suitable for lighter sweeping work, as for dwellings, offices and the like, wherein the individual units, preferably the oval ones, are arranged in a single row. Otherwise the construction and arrangement of the smaller broom is the same, as shown in Figs. 1, 2, 3, 4 and 5. 20 25 My push broom is extremely simple, durable and inexpensive to make. By the provision of the individual units 3-3', I am able to make use of the coarser as well as the medium weight broom corn heads, which when securely wound upon the small wooden cores 3^a, enables me to produce a broom structure that will withstand long and hard usage, and perform the same work that is usually effected by the coarser rattan construction in common use, for street and other rough and heavy sweeping. By the 30 35

use of broom corn, in which the twigs or bristles are generally of smaller caliber or gage than the rattan, my push brooms will sweep cleaner and remove relatively fine dust 40 or particles, which the coarser variety of push brooms cannot sweep. Furthermore, the provision of the individual units 3-3' admits of removing and replacing any of the said units that become worn out or fail to withstand hard usage. This may be accomplished in a ready and simple manner, by knocking out the pins 5, and then removing the cores 3^a from the body 2, in a well-known manner. 50

Having thus described my invention, what I claim is:—

A broom including an elongated back, a series of units each comprising a core having an encircling bundle of broom corn bound thereto, said binding being arranged adjacent the upper end of the broom corn, said units being elliptical in cross section and flared outwardly at the tips, and having their wide faces arranged parallel to the 55 sides of the back and in overlapping relation, and a hood encircling the sides and ends of the back and projecting below the under face of the back and engaged with the adjacent units, the upper ends of the 60 cores extending into the back and the lower ends thereof projecting below the bottom edge of the hood. 65

In testimony whereof I affix my signature.

SAMUEL GREENBERG.
